UNITED STATES PATENT OFFICE

BERNHARD J. DRUEDING, OF PHILADELPHIA, PENNSYLVANIA

HAT

Application filed May 28, 1932. Serial No. 613,622.

This invention relates to hats, and has for an object to provide a hat with an improved type of sweat band embodying new and improved features of convenience, comfort and dependability.

A further object of the invention is to provide a sweat band for a hat composed of an integral sheet of material such as leather, being pressed to form a bead outwardly flared 10 when secured in the hat and forming a rolled edge.

A further object of the invention is to provide a sweat band so constructed that it, of its own inherent properties, forms a cushion 15 between the band proper and the hat.

The invention therefore comprises a sweat band for use in a hat, and a hat including the sweat head, said sweat band being constructed of leather or similar material cut with its 20 opposite edges upon concentric arcs, with the outer arcuate edge turned inwardly to form a gathered seam member, the folding being produced by mechanical means for pressing the material to reduce its thickness along 25 spaced lines forming between the lines a bead which is curved so that when seamed in the hat, it curves outwardly.

The drawing illustrates an embodiment of the invention and the views therein are as 30 follows:

Figure 1 is a view of a fragment of a hat, made in accordance with the present invention,

Figure 2 is a similar fragment showing 35 the sweat band as it is first introduced into the hat and stitched,

Figure 3 is an enlarged detail view of the sweat band in section,

Figure 4 is a view of the sweat band in plan, 40 and

Figure 5 is a view of the sweat band in plan with the outer arcuate edge turned inwardly to form a folded strip.

Like characters of reference indicate corresponding parts throughout the several views.

The hat which is included in the present invention, may be of any type found desirable. The hat 10, as shown in the drawing, 50 is only illustrative and is not even intended

to properly represent any hat, but merely discloses how a hat may be formed to include a sweat band of the particular type shown in the drawing.

The sweat band 11 is cut with its opposite 55 edges upon concentric arcs as shown at Figure 4. This comprises not only that section which lies next to the head of the user, but also integrally therewith the strip which is folded between that section and the crown 60 of the hat. The section last referred to is indicated at 12. The section 12 is segregated from the section first referred to in any approved manner as by forming grooves 13 by pressure. When the sweat band is made of 65 leather, which is the approved material, the grooves 13 pressed therein will be retained as the facility of leather to maintain pressed in designs is well known.

Between the lines 13, a bead 14 is formed. 70 In the operation of pressing in the grooves 13 and the formation of the bead 14, the bead is also preferably given a transverse inclination as indicated in enlarged detail as in Figure 3 and as appears in the hat at Figure 75 1. This forms a roll edge, protecting the corner junction of the brim to the crown of the hat.

As will be noted from Figure 5, when the outer arcuate line is turned inwardly, it occupies an arcuate position of less extent than its own length, hence, a fullness is provided which is represented at Figures 2 and 5. This 80 serves to form a cushion between the section of the band which lies next to the head of user and the crown of the hat which adds 85 greatly to the comfort of the wearer; also spacing the band somewhat away from the crown of the hat and therefore preventing 90 soiling of the hat by perspiration seeping through the band.

The band therefore performs the double function of providing the outwardly turned beaded edge 14 as well as the cushion intervening between the band proper and the crown. 95

This is all brought about by the making of the two sections of integral material such as leather although it is to be understood, of course, that the invention is not limited to 100

leather but includes the use of any sheet material found efficient for the purpose.

Of course, the hat herein illustrated may be modified and changed in various ways 5 without departing from the invention herein set forth and hereinafter claimed.

The invention is hereby claimed as follows:

1. A hat comprising a crown and brim, and 10 a sweat band composed of an integral sheet of material with its opposite edges formed as concentric arcs and the outer arcuate edge folded inwardly forming a fulled strip, said fulled strip being stitched to the crown adjacent to the fold and lying intermediate the 15 crown and major part of the band.

2. A hat comprising a crown and brim, and a sweat band of sheet material of curvilinear form, said band having a bead formed adjacent to its convex edge with the margin 20 defined thereby folded inwardly against the major part of the band, said inturned edge having a fullness stitched to the crown of the hat adjacent to the fold and interlying the major part of the band with the bead inclined 25 over the junction of the crown and brim.

In testimony whereof I have signed my name to this specification.
